COLLAPSIBLE ENEMA BAG OR SIMILAR ARTICLE

John C. Ilg, Fitzwilliam, N.H., assignor to Elliot Laboratories, Inc., Fitzwilliam, N.H., a corporation of New Hampshire

Filed Feb. 28, 1964, Ser. No. 78,823

Term of patent 14 years

(Cl. D83—1)

FIG. 1

FIG. 4

FIG. 2

FIG. 1 is a perspective view of a collapsible enema bag or similar article embodying my new design.

FIG. 2 is a perspective view thereof.

FIG. 3 is a rear elevational view thereof.

FIG. 4 is a side elevational view thereof.

The essential features of my design reside in the full line showings on the drawings.

I claim:

The ornamental design for a collapsible enema bag or similar article, substantially as shown and described.
